SHOE SHINE BOX OR SIMILAR ARTICLE

Melvin A. Goldfeder, Rockville Centre, N.Y., assignor to Swank, Inc., Attleboro, Mass.

Filed Dec. 14, 1970, Ser. No. 25,477

Term of patent 14 years

Int. Cl. D28—99

U.S. Cl. D86—11

FIG. 1 is a rear elevational view of a shoe shine box, or similar article, showing new design;

FIG. 2 is a side elevational view thereof;

FIG. 3 is a front elevational view thereof;

FIG. 4 is a top plan view thereof;

FIG. 5 is a bottom plan view thereof; and

FIG. 6 is a perspective view thereof with the cover plan swung away from the body to expose the interior of the body.

I claim:

The ornamental design for a shoe shine box or similar article, as shown.
